CLAMPING MEANS

Christopher L. Hardwick, Cleveland, Tenn.

Application November 2, 1945, Serial No. 626,325

3 Claims. (Cl. 292—288)

1

This invention relates to improvements in clamping means for securely holding door and drawer panels of stoves and the like in place during shipment.

The principal object of the present invention is to provide clamping means particularly adaptable to be applied to a stove or the like for securely and uniformly clamping the stove compartment doors and drawer in place and preventing the same from becoming dislodged and damaged during shipment.

Another object is the provision of simple, inexpensive and interchangeable clamping means adaptable to be readily applied and removed from a stove or the like.

Still another object is to provide improved clamping means having cushioning means associated therewith for assuring of a tight clamping without danger of the stove compartment panels becoming marred during shipment.

These and other objects and advantages will be apparent as the specification is considered with the accompanying drawings, wherein:

Figure 1 is a perspective view of a stove showing my improved clamping means positioned thereon, and with one compartment door partly broken away to disclose the front frame;

Figure 2 is a section on the line 2—2 of Figure 1;

Figure 3 is a section on the line 3—3 of Figure 1;

Figure 4 is an exploded perspective view of one form of clamping device; and

Figure 5 is a perspective view showing a modified form of washer.

Referring more particularly to the drawings, wherein like numerals designate like parts throughout the several views, 1 generally designates a table top stove or range comprising a top burner compartment 2, a main centrally arranged baking and broiling oven 3, side warming compartments 4 and a bottom sliding utility drawer 5. The oven and side compartments are closed by conventional enamel or porcelain finished paneled doors 6 and 7, respectively, each of which is insulated in the conventional manner, as illustrated in Figures 2 and 3, and supplied with suitable handles 8. In the stove or range illustrated in Figure 1, the main oven door 6 is hinged by suitable hinges, not shown, to the front frame 9 so as to swing downwardly about a horizontal axis and the side doors 7 are similarly hinged to swing outwardly in opposing directions about vertical axes. When closed, the doors and utility drawer will flatly engage the

2

front frame 9 and the side edges of the adjacent door and drawer panels will be spaced slightly from each other to provide clearance and to permit of the assembly of the clamps about to be described.

Due to the particular arrangement of main oven and compartment doors and drawers in the stove illustrated, it is necessary to employ a plurality of clamps. Thus, one form of clamp 10 is assembled on each of the side compartment doors 7 and engages with the main oven door on either side thereof, and another form of clamping device 11 is applied to the front frame 9 at points intermediate the ends of the utility drawer 5 and the side compartment doors 7 so that the respective doors and drawer are securely clamped or anchored in closed position, as shown in Figure 1.

Referring more particularly to the clamps 10, referred to above, each clamp comprises a strip of sheet metal bent to form two oppositely extending, substantially parallel flat, relatively narrow, offset inner and outer tongues 12 and 13, respectively, connected at their inner ends by an integral flat web 14. The tongues extend in opposing lateral directions and therefore lie in substantially the same horizontal plane while the web 14 extends at substantially a right angle to the tongues. The innermost tongue 12 flatly engages with the rear wall 15 of the side compartment door 7 and is secured thereto by any suitable means such as a bolt or the like 16 which extends through apertures 17 and 18 in the tongue and wall, respectively. When the doors 6 and 7 are closed the web 14 will extend forwardly between the adjacent side edges of the doors and the outer tongue 13 will overlap and snugly engage the outer face of the compartment door 6, thus holding the latter tightly closed.

The space between the adjacent side edges of the doors 6 and 7 is sufficient to permit of preferably three-ply corrugated paper liner panel engaging strips 21, associated with and similar in shape to the metal clamps 10, being interposed therebetween. The paper strips will function as cushions to insure against the finish of the doors becoming marred or otherwise damaged. The positioning of the paper strips 21 between the side edges 20 of the oven door 6 and the webs 14 of the clamps causes the doors to become wedged together so that the doors will be retained in closed positions during shipment.

As previously mentioned, the bottom clamps 11 are applied to the front frame 9 at points intermediate the ends of the utility drawer 5 and the

side compartment doors 7, as best shown in Figure 1. Each of the clamps 11 comprises a piece of wire 22 threaded through an opening 24 in a metal stop nut 23. The wire 22 is folded over, as at 25, to form two substantially parallel strands or portions 26 of any suitable length which are twisted at their inner joined ends, as at 27, so that the stop nut 23 is retained in position thereon. The wire strands 26 are adapted to be inserted through apertures 27' in the front frame 9 of the stove at points preferably intermediate the top and bottom edges of the utility drawer 5 and the adjacent spaced side edges 19 and 31 of the side doors 7 and utility drawer 5, the stop nuts 23 engaging the frame, as shown in Figure 2. In these assembled positions, a preferably three-ply corrugated paper panel engaging cushioning strip 28, a large metal washer or disc 29 and a nut 30 are arranged in superposed relation, in the order named, on the free ends of each of the clamping wires 22, the strip 28, washer 29 and nut 30 being formed with apertures 28', 29' and 30' respectively, for this purpose. The free ends of the strands or wires 26, extending through apertures 27' in the nuts 30, are pulled therethrough by any suitable tool so that the relatively large heavy flexible paper strips 28, which overlap the drawer 5 and doors 7, are forced tightly against the faces of the respective door and drawer panels, also as best shown in Figure 2. The free ends of the strands 26 are then bent over the nuts 30 in opposing directions, and if desired twisted about themselves, so that the clamping units are securely retained in locked clamping positions relative to the door and drawer panels, the extended ends of the strands being of considerable length for this purpose. While the paper strips 28 are preferably rectangular in shape, it will be understood that the same may be of circular or any other desired configuration, provided the strips will overlap and flatly engage the adjacent side edges of the respective side doors and utility drawer and prevent the latter from becoming marred or otherwise damaged. From the foregoing it will be seen that the clamps 11 securely clamp the lower ends of the side doors 7 and the utility drawer 5 in closed positions while the top clamps 10 clamp the upper ends of the doors 7 and oven door 6.

In Figure 5, I employ a slightly modified form of washer 39 which is provided with an additional opening 40 adjacent opening 29' thus forming a web 41. With this form of washer the nut 30 may be eliminated. Thus the free ends of the strands 26 will be inserted through the openings 40 and 29' respectively and twisted upon each other and about the web 41, to tightly clamp the washer and the strip 28 in place, as shown in Figure 5.

It will also be understood that the clamps 10 and 11 are interchangeable and may readily be substituted one for the other, in an obvious manner. While preferred embodiments of my novel clamps are shown and described, various changes and improvements may be made without departing from the scope and spirit of the appended claims.

Having thus described my invention what I claim is:

1. A clamp for holding spaced panels to the front frame of a stove comprising a flexible wire member having a free end adapted to extend forwardly through an opening formed in the front frame and between and beyond the edges of adjacent panels, stop means on the rear end of said wire member engageable with said frame, a cushioning means carried by said wire, said cushioning means being adapted to overlap and engage the front faces of said panels, a flat plate carried by said wire member and engageable with said cushioning means, and means on the plate to which the free end of said wire member is secured for holding said cushioning means in clamping engagement with said panels and for holding said panels in closed positions.

2. A clamp for holding spaced panels to the front frame of a stove comprising a flexible wire member of substantially U-shape and having free ends adapted to extend forwardly through an opening formed in the front frame and between and beyond the edges of adjacent panels, a stop member carried by the inner end of said wire member and engageable with said frame, a cushioning strip carried by said wire member, said cushioning strip being adapted to overlap and engage said panels, a substantially flat washer carried by said wire member and engageable with said cushioning strip, said washer having perforations through which the free ends of the wire member extends, and means on the washer between said perforations to which the free ends of said wire member are attached for holding said washer against said cushioning strip whereby the latter is held in clamping engagement with said drawer and door panels and said panels are clamped in closed positions.

3. A clamp for holding spaced panels to the front frame of a stove comprising a flexible wire member having a free end adapted to extend forwardly through an opening formed in the front frame and between and beyond the edges of adjacent panels, stop means on the rear end of said wire member engageable with said frame, a cushioning means carried by said wire, said cushioning means being adapted to overlap and engage the front faces of said panels, a flat plate carried by said wire member and engageable with said cushioning means, said plate being cut away at spaced intervals to provide a web member to which the free end of said wire member is secured for holding said cushioning means in clamping engagement with said panels and for holding said panels in closed positions.
